FASTENING-INSERTING MACHINE

Fred N. La Chapelle, Beverly, Mass., assignor to
 United Shoe Machinery Corporation, Borough
 of Flemington, N. J., a corporation of New
 Jersey

Application July 19, 1938, Serial No. 220,064

91 Claims. (Cl. 1—32)

This invention relates to machines by which fastenings may be inserted, it being herein illustrated in connection with an apparatus for attaching to shoes heels or heel-portions, as a lift of rubber or the like.

In Letters Patent of the United States No. 2,161,827, La Chapelle and Ashley, June 13, 1939, there is disclosed and claimed a machine of the character above indicated, in which the fastenings, formed in connection with each attaching operation from strings of adhesively coated, fibrous material, are subjected to the action of an inserting die having associated with it a heel-holder and a pricking and driving assembly operating through the die-passages. There is, further, means for feeding strings of the fastening-material through predetermined distances and severing therefrom separate fastenings. These are transferred to the inserting mechanism, where they are moistened to insure their retention in the work and are acted upon by different groups of drivers, as those at the breast of the heel and the remainder of the set. While the machine of the application effects the attachment of heels satisfactorily, it is an object of the present invention to further increase its efficiency and convenience.

In the attainment of the above object, my improved machine is so organized that the fastenings may readily be inserted in accordance with any one of a plurality of designs, inserting mechanisms corresponding to different designs being mounted upon such a movable carrier as a rotatable turret, simple in form and effectively supported, for presentation at an operating position at which is a work-support. There is novel means by which the string fastening-material is supplied, and a severing or forming member is mounted upon the carrier for each inserting mechanism and by which the fastenings are cut from the strings, they being thereafter transferred to the inserting mechanism by a member common to plural inserting mechanisms, this preferably being mounted separately from the carrier and playing a part in the cutting or forming operation. Improvements are made in the string-delivering assembly, the pricking and driving assembly and its mounting and in the structure of the co-operating die. Means for actuating the drivers is provided whereby, as they encounter resistance, for example at the end of a pricking stroke or upon contact with an obstruction in the work, they not only yield, but the force which they apply decreases. Both the pricking and driving strokes of the inserting mechanism are

most effectively made by a single rotation of a cam. In the movement of the turret to bring the chosen inserting mechanism into operating position at the work-support, it is indexed automatically and by means which also serves to release the particular driver-assembly for operation only when it is thus positioned, all the others being locked, so they may accurately be engaged by actuating mechanism common to all and which is associated with the work-support. There is also a manually controlled lock by which the operator maintains the proper relation of the released driver-assembly to the common actuating mechanism. The string-feeding mechanism is arranged upon the machine-frame for ready removal as a unit, and to prepare for the movement of the turret or carrier when the inserting design is to be changed, there is means by which the ends of the strings advanced into the turret during the preceding operation may be retracted manually to clear the turret and then returned, ready for severing during the succeeding operation, this manual means, at the same time, disconnecting and reconnecting the mechanism which produces the power-feed. This power-feed includes novel means for introducing lost-motion into the actuating connections to transmit from the driver-assembly only sufficient movement to cause the correct advance of the strings. An improved fastening-cutting and transferring mechanism of extreme simplicity is utilized, in which a compound movement is imparted to a loader-block, so it applies a considerable force slowly to shear the strings and then shifts the block rapidly to deliver the fastenings thus formed to the inserting mechanism. Alterations are made in the liquid-supplying mechanism to cause the delivery of the die-passages of an adequate but not excessive quantity of the liquid, this supplying mechanism being especially adapted for use with the plural inserting mechanisms.

In the accompanying drawings, one of the several possible forms of the improved machine is illustrated,

Fig. 1 showing it in front elevation, with parts broken away;

Fig. 2 being a similar side elevation;

Fig. 3, an enlarged central vertical section through the upper portion of the apparatus, in a plane extending from front to rear;

Fig. 4, an irregular horizontal section, taken generally along the line IV—IV of Fig. 3;

Fig. 5, a fragmentary horizontal section in a plane just above the die and loader-block;

Fig. 6, a broken top plan view of one of the feeding mechanisms;

Fig. 7, a vertical section therethrough upon the line VII—VII of Fig. 6;

5 Fig. 8, a detail in separated perspective of one of the driver-assemblies with its mounting;

Fig. 9 is a like view of one of the inserting dies, with its tubes, a heel-holder, shear-plate and a portion of the turret-plate;

10 Fig. 10 shows similarly the liquid-delivering connections between the fixed frame and the rotatable turret, and

Fig. 11, a vertical section through a shoe with a rubber lift which has been attached by the 15 machine.

The frame of the machine is shown as consisting of a casing having a base-section 10 carrying an intermediate section 12, upon which is supported a top section 14. The securing means 20 for the sections and the openings with which they are provided to permit the passage of the elements and give access to the interior of the casing, need not particularly be described. Guided in spaced vertical ways at the front of 25 the section 12 is a bracket 16, upon the upper horizontal portion of which is a shoe-supporting jack 18 with its toe-rest 20 and back-stop 22. These shoe-engaging elements may be shifted from an outward work-receiving position, as illustrated in Fig. 2 of the drawings, to an operating position, partially within the casing, as appears in Fig. 3. The weight of the bracket and jack may be counterbalanced by tension-springs 24, 24, joining the bracket to the casing. Pivoted 30 at 26 upon the under side of the bracket is a block 28 provided with a vertical threaded opening receiving a screw 30 mounted to turn upon the horizontal arm of a slide 32. This slide is arranged for vertical adjustment upon a lower 35 block 34 guided by a fork 35 depending from its lower portion. At the bottom of the block 34 a roll 36 is rotatable, it resting upon a cam 38 fast upon the forward extremity of a horizontal shaft 40 journaled in the casing-section 10. The shaft 45 40 is driven through reduction-gearing 42 and a single-rotation clutch 44 from a main driving shaft 46 turning in the casing parallel to the shaft 40 and which receives power from belt-gearing 48. The clutch may be controlled by a 50 rod 49 extending to the front of the machine.

To raise and lower the jack to apply preliminary or measuring pressure to the work, consisting of a jacked shoe S and a heel or heelportion H held in co-operation with inserting 55 mechanism, which will be described later, a pinion 50, resting upon the slide 32, is fast upon the shank of the screw 30 and has a projection 51 turning in the arm of the slide and in the 60 top of the block 34. Meshing with the pinion is a rack 52, guided for horizontal movement upon the frame. Connections 54 join the rack to a treadle 56, movable at the bottom of the casing-section 10 and normally elevated by a tension-spring 58. The effect of this preliminary-pressure mechanism is as in Letters Patent of the 65 United States No. 446,885, Pope, February 24, 1891. Final pressure to clamp the work for the pricking of fastening-receiving openings and the 70 insertion of the fastenings is effected by the rotation of the cam 38 after the clutch 44 has been tripped by rearward movement of the rod 49. The cam in its rotation forces the block 34 up against the slide 32, which raises the block 28 and the jack. To vary the degree of clamping 75

pressure applied, more or less lost-motion may be introduced between the top of the block 34 and the upper arm of the slide 32. For this purpose, the slide may be raised or allowed to be lowered upon the block 34 by an eccentric 66, surrounded by a block upon which said slide rests in its initial position. This eccentric is fast upon the inner end of a short spindle 62 rotatable in the forward wall of the casing by a handle 64 and there locked.

To operate upon the jacked shoe and the lift to be applied, there is furnished a plurality of inserting mechanisms, each arranged in accordance with a different inserting design and equally spaced about a rotatable turret or carrier T, so anyone of the mechanisms may be brought to operating position. Save for the difference in the design, these mechanisms may be the same, so but one need be considered in detail. Depending from the casing-section 14 near the center of the machine is a cylindrical bearing member 70 (Fig. 3), having at its lower extremity an enlargement 72. About the member 70 the turret T is rotatable, it being stepped upon the portion 12. The turret has a central hub 74 about which is a ring 76 having at its periphery uniformly spaced vertical guide-portions 78 corresponding in number to the inserting mechanisms, in which guide-portions combined pricking and driving assemblies A may reciprocate. In the present embodiment of the invention, there are six of these guides with their assemblies. To downward extensions 80 from the ring 76 a circular plate 82 is secured, this turning in an opening in the top of the casing-section 12. In this plate, vertically aligned with the driver-assemblies, are dies 84 provided with passages 92 through which the pricking stroke is made and the fastenings are driven. They also furnish abutments against which the heels to be attached are forced. Below the dies are heel-holders 86 having arms between which is a space for the introduction of the lift to be attached (Fig. 9). The heel-holder may have turning about vertical spindles in its opposite arms, rolls 81, 87, the peripheries of which may be knurled to increase their retentive effect. The space between the rolls is such that they slightly indent the rubber to hold the lift securely in place. To avoid mutilation of the lift-wall, when pressure is applied to the work and the lift rises against one of the dies 84, the rolls are permitted to shift longitudinally of their supporting spindles. Consequently, there is no relative movement between the lift and the portion of the retaining means which contacts with and might mar it. Situated upon the turret-plate 82 inwardly from the dies and holders are shearing plates 88, having openings 89. Both the die-passages 92 and the shear-openings 89 are arranged in accordance with a nailing design corresponding to that of the more directly associated drivers. Under each of the shear-plates is a fiber-delivering assembly D. The lowermost portion of the turret consists of a head t through which water or other liquid may be supplied to moisten the fastenings. When a jacked shoe is pressed against a lift in the holder 86 of the die which is in operating position, upward displacement of the plate 82 is resisted by its engagement with the under surface of an abutment-yoke 90, secured to the top of the casing-section 12 at 91 and extending across the front of the machine. Each of the dies 84 is secured in a depression at the under side of the turret-plate by screws 93 and dowel-pins 94. The passages 75

92 are preferably formed in tubes 95 inserted in openings in the turret-plate and having heads 96 seated in a depression in the die-plate (Fig. 9). From the lower extremities of the tubes, which with the cooperating portions of the turret-plate may be considered as portions of the die-plate, frusto-conical projections 98 extend through corresponding openings 99 in said die-plate. These projections are adapted to enter and compress the rubber lift or heel during the operation upon it. Below the die, the heel-holder 86 is attached to the turret-plate by screws 100.

As is shown in Fig. 3 and in greater detail in Fig. 8, each driver-assembly A has a slide 102 movable in vertical ways upon a portion 78 of the turret T. From the slide is an outward projection 104, and this contains horizontal ways in which a driver-holder 108 is separably retained by a spring-actuated latch 106 entering an opening 107 in the slide. To the under side of the holder a driver-plate 110 with its backing-plate 112 is attached by screws 114 threaded upwardly into the holder. A set of drivers 116, serving also as awls, depends from the plate 110, with their heads held against upward displacement by the plate 112. Since the breast-drivers, of which two are shown and designated by the character 117, may be required to move through a less distance than the remainder of the set because some such obstruction as a metal shank-reinforcement may lie in their path, they are mounted upon the holder 108 to move independently. In the holder are vertical ways to receive a slide 118, at the bottom of which the breast-driver-plate 119 is secured by screws 120, it occupying a recess 122 in the forward portion of the plate 110. Upon depression of the latch 106 by a hand-tool inserted in the opening 117, the holder may be removed from the machine, to be replaced by an assembly corresponding to a different inserting design or for the replacement of broken drivers.

To give to the drivers 116 and 117 their vertical movement to prick the lift, the base which may have been attached to the shoe, and the heel-seat of the shoe itself, and to force the fastenings from the die-passages 92 into the work, there are guided at 128 for reciprocation in the casing-section 12 side-rods 130. These are joined at their upper extremities outside the casing-section 14 by a top-girt 132 extending across the front of the machine, while below, they are connected by a cross-girt 134 (Fig. 1). Below the girt 134, a crosshead 136 is movable vertically in guides 138 upon the casing-section 10, the side-rods passing through this crosshead at 140. Rotatable upon the upper and lower portions of the crosshead and at opposite sides thereof are rolls 142, 142 (Fig. 2) engaged by a double cam 144 fast upon the shaft 40 and which acts to both raise and lower the crosshead. Spaced from each other at the top of the crosshead are brackets 146, 146, between which is trunnioned at 148 a cylindrical casing 150 containing a plunger 152 operating against a compression-spring 154 within the cylinder. Outside said casing, the plunger is joined to the center of a toggle-lever 156, 156, the upper extremity of which is pivoted between the brackets 146, while the lower end is joined to the cross-girt 134. Through these connections, power is yieldably transmitted from the shaft 40 to the top-girt 132.

At the center of the top-girt, in vertical alignment with the die 84 situated in operating position, is secured a block 158 having at its under side a recess in which are spaced horizontal ways

160, 160 curved in an arc having its center at the axis of the turret T (Fig. 4). With the top-girt in its normal elevated position, these ways are located vertically to receive, as the turret is turned, opposite arcuate projections 162, 162 5 (Fig. 8), these being shown as provided by the edges of a curved plate 164 attached to the slide-projection 104 of each driver-assembly A by screws 166. By rotating the turret manually, as any one of the driver-assemblies with its associated die and shear-plate is brought to the front of the machine into operating relation, the driver-slide-projections 162 will enter the top-girt-ways 160, so reciprocation of the top-girt through the connections just described will impart movement to the drivers. To insure the correct presentation of the traveling slide-projections to the normally stationary ways, each of the slides 102 is locked in the desired position at all times, except when the projections have 10 entered the ways. This is accomplished by a plunger 170 (Fig. 3) mounted to move horizontally in each guide-portion 78 of the turret and urged inwardly by a spring 172. The plunger at its outer end is arranged to enter an opening 174 25 in the corresponding driver-slide, while at its inner end, it carries a roll 176 movable along a cam-surface 178 extending about the bearing member 70. The contour of this cam-surface is such that in all positions of the turret, save when the projections 162 have entered the ways in the block 158, the plunger will be held out by the surface 178, so it occupies the opening 174, and the slide-projections are secured in horizontal registration with the ways. As the rotation of the 30 turret brings the different driver-assemblies into operating relation, the projections of a thus-locked slide enter the ways as the roll 176 reaches a depression 180 in the surface 178. This allows the spring 172 to retract the plunger from the 40 opening 174, unlocking the slide, ready for the actuation of the drivers. To hold, relatively to the top-girt 132, the turret and the slide which have been released in this manner, with its drivers 116, 117 in registration with the die-passages 45 92 ready for operation, a plunger 182 extends vertically through the top-girt and is forced by a spring 184 which surrounds it into an opening 186 in the plate 164, registering with the opening 107 in the projection 104. To the upper extremity 50 of the plunger is connected a hand-lever 188 fulcrumed by a link 190 upon the top-girt (Fig. 1). When the operator desires to change the nailing design, he may raise the plunger 182 with one hand and turn the turret with the other, each 55 of the plungers 170 producing automatically the indexing of the turret and the release of each driver-assembly as it reaches the operating position. When the lever 188 is freed, it will lock the chosen driver-assembly in operating position. 60 The capacity of the breast-drivers 117 to move independently of the remainder of the set, already referred to, is provided for by yieldable actuating means carried by the top-girt. Pivoted at 192 in a housing 193 secured to the front of the 65 top-girt is a toggle-lever 194, 194, having pivoted to its lower extremity a contact member 195 guided in the housing and resting upon the top of the breast-driver-slide 118. To the center of the toggle a rod 196 is united, this passing 70 through a guide 197 on the top-girt. Surrounding the rod between the toggle and the guide, a compression-spring 198 is interposed. With the toggle slightly broken in the direction of the guide, the spring normally holds the slide 118 75.

seated in the recess 122 in the plate 110. The strength of the spring is sufficient to prevent yield of the drivers 117 during their usual pricking action, but if they meet any object offering undue resistance, these drivers remain stationary, the spring compressing without injury to the parts.

With the turret located as just described, the machine may be started by movement of the rod 49 to cause the cams 144 to be rotated by the shaft 48 through 360°. The contour of these cams is such that the side-rod 130 are reciprocated twice during each operating cycle. The first movement is for the purpose of pricking the lift, heel-base and heel-seat of the shoe to points at or near the plate in the last which is in the shoe. The second stroke is of less length and is for the purpose of inserting the fastenings in the pricked openings. The yieldable actuating connections for the drivers, including the spring 154, permit a full pricking movement to be made and stopped at a predetermined point. During the passage of the drivers through the work, the resistance of the spring to compression is sufficient to impart a substantially positive advance to the drivers. The stopping of the pricking movement may result from the engagement of the ends of the drivers with the last-plate or may be after travel through a less distance under the control of an element of the machine. Figs. 1 and 2 of the drawings show stop-collars 200 surrounding the side-rod and arranged to receive contact of the top-girt or a part fixed thereto. These collars may be divided for convenience in application and are of different thicknesses, so the pricking stroke may be varied in accordance with the work in hand. When the pricking movement of the drivers is stopped in either of the ways just mentioned, the toggle 156, 156, which is normally slightly broken in the direction of the spring 154, will further decrease the angle between its arms, compressing the spring and allowing continued descent of the crosshead 136 without movement of the cross-girt 134, the side-rod and the drivers. It should be noted that as the toggle-arms approach each other, the force which they apply to the spring increases, while that impressed upon the drivers decreases. Therefore, the lowering of the cross-head may continue with compression of the spring, less force being exerted which may tend to puncture the last-plate or injure portions of the machine. The effect of the toggle 194 and spring 198, in the yield of the breast-drivers 117, is similar to this. In each case, the variable force is transmitted from the girt by which they are actuated. During the second or inserting stroke of the cycle, the drivers then do not meet sufficient resistance to cause compression of the spring 154, and the fastenings enter the work to definite depths. The extent of this movement and therefore the depth to which the fastenings are sunk in the lift H, may be varied by changing the position of the cross-girt 134 upon the side-rod. To this end, the girt is supported between lower nuts 202 and upper nuts 204 threaded upon the rods. By backing off one set and turning up the other, the vertical relation of the drivers to the dies may be adjusted.

70 Strings of fiber f, from which the fastenings are formed, are delivered to the shear-plates 83 of the turret T in two sets, which may be of seven each, from two feeders F, F (Fig. 1). These feeders are situated at opposite sides of the casing section 12 and are supplied with the fiber from

reels 206 rotatable about spindles 208 mounted in housings 210 carried by the casing-section 12 and closed by hinged covers 212. Each feeder is mounted upon a plate 213 covering an opening of the casing, so said feeder may be removed as a unit for inspection or repair. The feeders may be identical in construction, so but one will be described. As best illustrated in Figs. 6 and 7, the feeder has a pair of rolls 214, 216 provided with registering peripheral grooves 218 through 10 which the strings of fastening-material pass and which may be toothed to better engage said strings. The shaft 219 of the roll 214 is journaled in a supporting frame 220 secured to the cover 213, while the shaft 221 of the roll 216 is journaled in a swinging frame 222, hinged at 224 to the frame 220. The swinging frame is acted upon by a spring 226 surrounding a rod 228 pivoted at 230 to the fixed frame. The outer extremity of the spring abuts against a nut 232 threaded upon the rod. By adjusting this nut, there may be varied the force with which the rolls bite the strings to insure advance. At 234, the rolls are geared to rotate together. The driving force is applied to the shaft 219 of roll 214 through a sleeve 236 surrounding the shaft and having fast upon it a gear 238. With this gear meshes a vertically reciprocatory rack 240 guided in the frame 220 and receiving movement through a link 242 pivoted to it and to a second link 244, which, in turn, is pivoted to a collar 246 secured to the adjacent side-rod 130. Upon the sleeve, staggered pawls 248, 248 are pivoted and are forced by spring-actuated plungers 249 into engagement with the teeth of a ratchet-wheel 250 fixed upon a short sleeve 251 surrounding the shaft 219. In a flanged end of the sleeve 251 is a circular series of openings 252, any one of which may receive a projection 253 from the flanged extremity of still a third sleeve 254 about 40 the shaft. To the outer extremity of the sleeve 254, outside the plate 213, a hand-wheel 255 is secured. A long spline 256 in the sleeve 254 receives a feather 257 in the shaft. An expansion-spring 258, interposed between the inner face of the plate 213 and the flange of the sleeve 254, urges said sleeve and hand-wheel in, so the projection 253 occupies one of the openings 252. In this relation, intermittent rotation imparted by reciprocation of the rack 240 through the pawls 248 to the ratchet-wheel 250 is transmitted through the sleeve 251, the projection 253, the sleeve 254 and the feather 257 to the shaft 219. This causes the rotation of the rolls 214 and 216, and the feeding up of the fiber strings step by step from the reels 206. If the operator wishes to withdraw or advance the strings manually, in connection with rotation of the turret to change the inserting design, the sleeve 254 is pulled out by the hand-wheel, until the sleeve-projection 253 leaves its opening 252. This uncouples the ratchet-wheel 250 from the shaft 219, so the latter may be rotated through the hand-wheel without interference by the power mechanism. When the machine is at rest, there is a space between the lower ends of the drivers and the upper face of the turret-plate 82, into which space may be moved the transferring means which delivers fastenings from the shear-plate-openings 89 to the die-passages 92. In the travel of the drivers through this space, the descent of a side-rod causes the link 244 to swing the link 242 from contact with a surface 260 upon the rack 240 into engagement with a surface 262 thereon. During this movement, which is indi- 75

cated by a dash-line in Fig. 7, the rack 240 remains at rest, but when the drivers have reached a point at which the inserting stroke is to terminate, contact of the link with the surface 262 causes downward travel of the rack corresponding to a distance equal to the difference between the pricking and fastening-inserting strokes of the drivers and therefore to the length of the fastenings themselves. This may be communicated through the connections previously indicated to the rolls 214, 216, the resulting rotation of which rolls will draw off from the reels 208 measured lengths of the fiber strings. When the extent of travel of the drivers is varied by their contact with the last-plate or because of adjustment of the stop-collars 200, the length of the fiber fed is correspondingly altered. Reverse rotation of the rolls during the idle oscillation of the pawls may be prevented by detents 264, 264 pivoted upon the frame 220 and urged against the periphery of the ratchet-wheel 250 by spring-actuated plungers 266. Backlash in the rolls is prevented by a friction-segment 268 movable upon the frame 222 and forced against the roll 216 by a spring 270.

From the feeders, the strings pass through tubes 272, which are held at their upper ends in a terminal-bar 273 secured to a bracket 274 attached to one side of the casing-section 12 (Fig. 1). For each of the shear-plates 88 there is depending from the turret-plate 82 a support 275 forming a part of one of the fiber-delivery-assemblies D and to which is secured a terminal-bar 276. From the bar rise tubes 272 (Figs. 3 and 9) terminating above in a plate 280 in which are arranged tube-receiving openings in registration with the openings 89 of the shear-plate, this relation being maintained by dowel-pins 282. Thus, the strings, as they are measured off by the feeders for each inserting operation, are carried through the shear-plate to the amount necessary for the fastenings, ready to be severed and transferred to the die-passages 92 in position for driving. This transfer is effected by a loader-block 290 (Figs. 3 and 5) cylindrical in form and arranged to turn in a recess at the outer end of a slide 292 reciprocable in horizontal ways formed at the bottom of the portion 72 of the bearing member for the turret. Through the loader-block are passages 294 corresponding to a plurality of inserting designs to be employed. In the present instance, three sets of these passages are illustrated for a like number of driver-assemblies and dies. If the other three designs carried by the turret T are to be used, another multiple block may be substituted. The block has a rearwardly extending arm 296, the end of which has an opening to receive a crank-pin 298 rising from a horizontal disk 300 fast upon the upper end of a shaft 301 journaled in the casing-bracket 274. The shaft is rotated to produce through the crank-pin the successive rotation of the loader-block in its slide and the reciprocation of said slide with the block. Power is supplied to the shaft 301 by a cam 302 (Fig. 2) fixed to the shaft 40. With the cam contacts a roll 304 rotatable upon a double bell-crank-lever 306 fulcrumed upon the casing-section 12. The roll is held against the cam by an expansion-spring 308 surrounding a rod 310 joined to a depending arm of the bell-crank. The other arm carrying the roll 304 is connected by a double link 312 to an eccentric 314 (Fig. 3) mounted for angular adjustment in the lower extremity of a rack 316 guided to reciprocate vertically upon the

back of the bracket 274. The eccentric may be turned to vary the normal relation between the link and rack by a short rod 318 acting through worm-gearing 320. Thereby registration may be established between the loader-block-passages 5 and one of the sets of openings with which there is to be registration at its opposite extremes of travel. The rack 316 has helical teeth and through similar gears 324, 324 turns the shaft 301. When the machine stops, the cam 302 and its connections locate the loader-block over the shear-plate 88 of the turret, which is then in operating position, the crank-pin 298 being in the dash-line position shown in Fig. 5 and the plate-openings and block-passages being in registration. The block preferably carries at its under side a perforated shear-plate 326 co-operating with the plate 88, the openings in the plate 326 and an upper plate 328 upon the block being held aligned with the block-openings by 20 dowel-pins 330. The fastening-material is delivered by the feeders F, F, through the openings in the shear-plate 88 into the loader-block-passages 294. When the crank-pin revolves to the full-line position in Fig. 5, as it crosses the center 25 removed from the inserting mechanism, it acts first to rotate the loader-block to such an extent that the openings in the plate 326 pass out of alignment with the openings of the shear-plate 88, cutting off measured lengths of the strings. 30 It should be observed that during this severing action, the pin is passing over a center in its revolution across the path of the slide, exerting its full force to divide the material without appreciable movement of translation of the loader-block. The continued revolution of the crank-pin through nearly 180° moves the slide 292 rapidly forward and turns the block but slightly upon the slide as it is advanced bodily, until, at the opposite center, the loader-block-passages 40 pass into registration with the die-passages 92. Here, they are retained long enough for the fastenings to be driven through the die into the work by the descent of the drivers 116, 117, after which continued movement of translation and 45 rotation of the block restores it quickly to its receiving position, with the crank-pin again at the point shown in dash-lines. When the loader-block is in its forward delivering position, a rearward extension 331 from the plate 326 covers 50 the shear-plate-openings. This guards against protrusion of the strings through said openings at all times, save when the block-passages are in position ready to receive them. By adjusting the eccentric 314, the vertical relation of the 55 rack 316 will be altered to produce normal registration of the block-passages 294 with the shear-plate-openings 89.

Moistening of the severed fiber pegs to increase their holding power in the work may be effected 60 by water or other liquid circulated by a pump 336 (Fig. 2) mounted in the bottom of the casing-section 12 and actuated by a cam-segment 337 secured to the shaft 40, this cam contacting with a roll 338 rotatable upon the upwardly extending 65 piston-rod 339 of the pump. The water is delivered to the pump by a pipe 335 from a tank 341, mounted at one side of the casing-section 12 (Fig. 1), and from the pump through a pipe 340 to a vertical passage 342 in the bracket 274 70 (Fig. 3). The passage 342 leads through the upper horizontal surface of the bracket, which is in close contact with the lower surface of the turret-head t (Fig. 10). A spring-pressed gasket 344 may be situated in a recess about the exit 75

of the passage 342 to prevent leakage between the surfaces. In the surface of the turret opposite the passage 342 is a series of passages 346, from each of which a pipe 348 radiates to a passage in the turret-plate 82, through which it delivers to a groove 350 in the upper face of the associated die-plate 84 (Fig. 9). In this groove 350, surrounded by a strip 351 of felt or other absorbent material, lie the heads 96 of the die-tubes 95, through the sides of which heads are horizontal slots 352. Upon the upward pressure-stroke of the pump 336, water is supplied to the groove 350, saturating the felt. This occurs while the drivers are rising from their pricking stroke, and while their ends close the tube-slots 352, avoiding undue flow into the passages 92. When the drivers are elevated after they have pricked the work, there is sufficient free water in the groove to flow through the slots 352 into the passages 92 and be there held by the lift H, which closes the lower ends of the passages. A segmental groove 354 in the upper surface of the head t registers with the passages 348 but terminates at its ends short of the inlet-pipe 342. A vertical passage 355 in the bracket 274 from the groove 354 is connected by a pipe 356 to the tank 341, thus allowing the water from the grooves 350 of all the dies other than that to which the inlet passage 342 is joined, to drain back to the tank. Upon the downward suction-stroke of the pump, which takes place immediately after the pressure-stroke, the excess of water which has been delivered to the groove 350, and that which may surround the rising drivers, will be withdrawn through the pipe 340, leaving only that in the passages 92 below the slots 352. This prevents drip from the passages in the loader-block 290, when this returns to its receiving position. As the drivers force the fastenings through the die into the work, said fastenings are moistened by the retained water to swell and render them adhesive, while the entrance into the rubber of the lift is made easier by the lubricating effect.

Let there be assumed a use of the machine when it is desired to change the nailing design. From the preceding operation, the strings f of fiber will be extending into the shear-plate 88, passing from the stationary bracket 274 into the revolving turret-bar 276. Therefore, the strings must first be withdrawn downwardly from the bar. The operator effects this by pulling out the hand-wheel 255, so the feed-roll 214 is disconnected from the power mechanism, and by turning the roll clockwise, as viewed in Fig. 7. By depressing the lever 188, the operator removes the locking plunger 182 from the depression 186 of the turret T and rotates said turret until the inserting mechanism arranged in accordance with a chosen design is at the front of the machine. As the turret is turned, the roll 176 of the driver-assembly which has been in the depression 180 in the turret-bearing, leaves this, and when the roll of the assembly which is to be employed reaches the depression, it is allowed to remain in and index the turret, simultaneously freeing the driver-slide 102. After this, rotation of the feed-roll 214 in an anti-clockwise direction will restore the strings to their positions in the shear-plate-passages with their ends against the block-plate 328, ready to be fed by the machine. The work to be done may be the attachment to a shoe S, having already secured upon it a base B, a lift H, consisting of rubber a molded about a cord b of

wood. With the jack 18 drawn out upon its bracket 16, the operator inserts the lift H in the holder 86, jacks the shoe and moves it back beneath the lift, gaging the position by the back-stop 22 and the toe-rest 20. Lowering the treadle 5 56, he rotates the screw 30 to raise the block 28 with the jack, until the surface of the base B contacts with the opposed face of the lift, and trips the clutch 44 by actuation of the rod 49. This initiates a power-cycle of the machine. As 10 the shaft 40 rotates, the cam 38 lifts the slide 34 to apply clamping pressure to the work, the upward displacing force upon the turret being resisted by its contact with the yoke 90. This 15 application of final pressure is succeeded by the descent of the top-girt 132 under the influence of the cams 144. The drivers 116 and 117, now acting as awls, are carried down through the die-passages 92 for their full stroke, the extent of which is determined by the yield of the spring 154 when the ends of the drivers strike the plate of the last in the shoe or when advance is stopped by the contact of the top-girt with the side-rod-collars 200. In this movement, the breast-drivers 117 yield against the spring 198, if they 20 find in their path an object which cannot be penetrated without danger of breakage. While the drivers are making their first, pricking stroke, the connections to the side-rod-collars 246 rotate the feed-rolls 214, 216 to advance the correct 25 lengths of fiber strings f for the formation of the fastenings to be inserted in the pricked openings, the ends of the strings rising through the shear-plate-openings 89 of the turret and the registering openings in the shear-plate 326 of the 30 loader-block into the loader-block-passages 294. This accomplished, the cam 302, revolving the crank-pin 298, first rotates the loader-block, before the descent of the drivers in their second, inserting stroke, to divide the strings in the 40 meeting plane of the shear-plates into discrete fastenings g and thereafter carries the block forward with the slide 292 to aline the block-passages with the die-passages 92. After the drivers have pricked the work and before the fastening-45 inserting stroke, the pump 336 is actuated by the cam 337 to force water into the groove 350 into the die 84 and the felt 351 therein, from whence it flows through the slots 352 into the lower portions of the die-passages 92 just above the lift-entering projections 98. As the drivers make their inserting stroke, actuated by the second period of rotation of the cams 144, the fastenings g in the loader-block-passages are driven from these through the die-passages into the work, as 50 is shown in Fig. 11, being moistened by the water in the lower portions of the passages 92 to increase their hold upon the work. Preferably, heads h, which are formed by the upsetting of the fastenings under the driver-pressure, lie in the 55 lift H at the outer face of the core b. During this driving movement of the side-rods 130, the feeding mechanisms F are ineffective, because of the idle movement of the links 242 between the rack-surfaces 260 and 262. The depth of insertion of the fastenings may be determined by the adjustment of the cross-girt 134 upon the side-rods, and the extent of the pricking stroke of the drivers and length of the severed fastenings by change of the stop-collars 200. In the initial 60 reverse movement of the drivers, the suction-stroke of the pump has largely withdrawn the water from the groove 350. As the drivers rise, they create suction in the portions of the die-passages 92 in which the water has been held, so 65 70 75 75

drawing it back that little or no drip will occur when the shoe with its attached lift is separated from the tube-ends 98. As the shaft 40 completes its rotation, the cam 38 releases the block 34, so 5 the jack is lowered, and upon removal of the work, the machine is ready for another operation.

Having described my invention, what I claim as new and desire to secure by Letters Patent of the United States is:

10 1. In a fastening-inserting machine, a work-support, a movable carrier, a plurality of inserting mechanisms mounted upon the carrier and movable thereby selectively into operating position at the work-support, a fastening-forming member mounted upon the carrier for each inserting mechanism, and means for supplying fastening-material to the forming member.

20 2. In a fastening-inserting machine, a work-support, a movable carrier, a plurality of inserting mechanisms mounted upon the carrier and movable thereby into operating position at the work-support, means for supplying fastening-material, and a member mounted upon the carrier at each inserting mechanism but spaced 25 therefor and arranged to cut the fastening-material for delivery to its inserting mechanism.

30 3. In a fastening-inserting machine, a work-support, a movable carrier, a plurality of inserting mechanisms mounted upon the carrier and movable thereby into operating position at the work-support, each inserting mechanism being provided with fastening-receiving openings, and a member common to plural inserting mechanisms and movable to deliver fastenings to the openings 35 of any one thereof.

40 4. In a fastening-inserting machine, a work-support, a movable carrier, a plurality of inserting mechanisms provided with opposite co-operating members mounted upon the carrier and movable thereby into operating position at the work-support, and a member mounted separately from the carrier and movable under the power of the machine to deliver fastenings to one of the opposite members of the inserting mechanism.

45 5. In a fastening-inserting machine, a work-support, a movable carrier, a plurality of inserting mechanisms mounted upon the carrier and movable thereby into operating position at the work-support, and a member mounted separately from the carrier and movable to form fastenings and deliver them to the positioned inserting mechanism.

55 6. In a fastening-inserting machine, a work-support, a movable carrier, a plurality of inserting mechanisms mounted upon the carrier and movable thereby into operating position at the work-support, means for supplying fastening-material, a member mounted upon the carrier at each inserting mechanism and arranged to cut the fastening-material for delivery to its inserting mechanism, and a member co-operating with the cutting member and movable to cut the material and to deliver it to each inserting mechanism.

65 7. In a fastening-inserting machine, a work-support, a movable carrier, a plurality of inserting mechanisms mounted upon the carrier and any one being movable thereby selectively into operating position at the work-support, and means for supplying fastening-material in strings for any one of the inserting mechanisms.

8. In a fastening-inserting machine, a work-support, a movable carrier, a plurality of inserting mechanisms mounted upon the carrier and movable thereby into operating position at

the work-support, means for supplying fastening-material in strings for any one of the inserting mechanisms, and means for dividing the strings into discrete fastenings and delivering them to only that inserting mechanism which is 5 in operating position.

9. In a fastening-inserting machine, a work-support, a movable carrier, a plurality of inserting mechanisms mounted upon the carrier and movable thereby into operating position at the work-support, and means for causing the inserting mechanism in operating position to perform successive work-pricking and fastening-inserting operations by movement through different distances, the associated inserting mechanisms being 15 maintained inactive.

10. In a fastening-inserting machine, a work-support, a movable carrier, a plurality of inserting mechanisms mounted upon the carrier and movable thereby into operating position at the work-support, each inserting mechanism being arranged in accordance with a different inserting design, means for causing the inserting mechanism in operating position to perform successive work-pricking and fastening-inserting operations, 25 a fastening-forming member mounted upon the carrier for each inserting mechanism, and means for supplying fastening-material to the forming member.

11. In a fastening-inserting machine, a work-support, a movable carrier, a plurality of inserting mechanisms mounted upon the carrier and movable thereby into operating position at the work-support, each inserting mechanism being arranged in accordance with a different inserting design, means for causing the inserting mechanism in operating position to perform successive work-pricking and fastening-inserting operations, 30 a fastening-forming member mounted upon the carrier for each inserting mechanism, and means for supplying fastening-material to the forming member during the pricking operation. 35

12. In a fastening-inserting machine, a work-support, a movable carrier, a plurality of inserting mechanisms mounted upon the carrier and movable thereby into operating position at the work-support, each inserting mechanism being arranged in accordance with a different inserting design, means for causing the inserting mechanism in operating position to perform successive work-pricking and fastening-inserting operations, 45 means for supplying fastening-material, a cutting member mounted upon the carrier at each inserting mechanism, and a movable member co-operating with the cutting member to cut 50 the material during the pricking operation and to deliver it to each inserting mechanism between the pricking and inserting operations.

13. In a fastening-inserting machine, a jack, a rotatable turret, a plurality of inserting dies and 60 co-operating drivers mounted upon the turret and movable thereby into operating position at the jack, a shear-plate mounted upon the turret for each die and provided with openings, and means for supplying fastening-material through 65 the shear-plate-openings.

14. In a fastening-inserting machine, a frame, a jack carried thereby, a turret rotatable upon the frame, a plurality of inserting dies and co-operating drivers mounted upon the turret and 70 movable thereby into operating position at the jack, means for supplying fastening-material, and a member movable upon the frame to deliver the fastening-material to the die which is 75 in operating position.

15. In a fastening-inserting machine, a jack, a rotatable turret, a plurality of inserting dies and co-operating drivers mounted upon the turret and movable thereby into operating position at the jack, a shear-plate mounted upon the turret for each die and provided with openings, means for supplying fastening-material through the shear-plate-openings, and a member having passages receiving the fastening-material 5 from the shear-plate-openings and movable to sever fastenings from the material.
16. In a fastening-inserting machine, a jack, a rotatable turret, a plurality of inserting dies and co-operating drivers mounted upon the turret and movable thereby into operating position 10 at the jack, a shear-plate mounted upon the turret for each die and provided with openings, means for supplying fastening-material through the shear-plate-openings, and a block movable upon the frame and having passages receiving the fastening-material from the shear-plate-openings, said block co-operating with the plate to sever fastenings from the material and to deliver them to the die which is in operating position.
17. In a fastening-inserting machine, a jack, a rotatable turret, a plurality of inserting dies and co-operating drivers mounted upon the turret and movable thereby into operating position 15 at the jack, and means arranged to reciprocate the drivers and prick the work upon the jack and thereafter to reciprocate said drivers to insert fastenings in the work.
18. In a fastening-inserting machine, a jack, a rotatable turret, a plurality of inserting dies and co-operating drivers mounted upon the turret and movable thereby into operating position 20 at the jack, and means for causing the drivers in operating position to perform successive work-pricking and fastening-inserting operations.
19. In a fastening-inserting machine, a jack, a rotatable turret, a plurality of inserting dies and co-operating drivers mounted upon the turret and movable thereby into operating position 25 at the jack, means arranged to reciprocate the drivers and prick the work upon the jack and thereafter to reciprocate said drivers to insert fastenings in the work, a shear-plate mounted upon the turret for each die and provided with openings, means for supplying fastening-material 30 through the openings of the shear-plate in operating position, and a member having passages receiving the fastening-material from the shear-plate-openings during the pricking operation and movable to sever fastenings from the material prior to the inserting operation.
20. In a fastening-inserting machine, a frame provided with a bearing-portion, a turret comprising a ring rotatable about the bearing-portion 35 and having downward extensions and a plate secured to the extensions, a plurality of driver-assemblies arranged to reciprocate upon the ring, and dies mounted upon the plate, there being one of the dies for cooperation with each driver-assembly.
21. In a fastening-inserting machine, a frame provided with a bearing-portion, a turret comprising a ring rotatable about the bearing-portion and a plate carried below the ring, a plurality of driver-assemblies arranged to reciprocate upon the ring, dies mounted upon the plate, there being one of the dies for co-operation with each driver-assembly, and a shear-plate carried by the turret-plate adjacent to each die.
22. In a fastening-inserting machine, a frame provided with a bearing-portion, a turret comprising a ring rotatable about the bearing-portion and a plate carried below the ring, a plurality of driver-assemblies arranged to reciprocate upon the ring, dies mounted upon the plate, there being one of the dies for co-operation with each driver-assembly, a shear-plate carried by the turret-plate adjacent to each die and provided with openings corresponding to the inserting design of the associated die, and a string-delivering assembly carried at the under side of the plate and having passages registering with those of each shear-plate.
23. In a fastening-inserting machine, a frame provided with a bearing-portion, a turret comprising a ring rotatable about the bearing-portion and a plate carried below the ring, a plurality of driver-assemblies arranged to reciprocate upon the ring, dies mounted upon the plate, there being one of the dies for co-operation with each driver-assembly, and a holder for a work-piece attached to the turret-plate beneath each die.
24. In a fastening-inserting machine, a frame provided with a bearing-portion, a turret comprising a ring rotatable about the bearing-portion and a plate carried below the ring and a liquid-distributing head attached to the under side of the plate, a plurality of driver-assemblies arranged to reciprocate upon the ring, and dies mounted upon the plate, there being one of the dies for co-operation with each driver-assembly and receiving liquid from the turret-head.
25. In a fastening-inserting machine, a frame provided with a bearing-portion, a turret rotatable about the bearing-portion, a plurality of driver-assemblies arranged to reciprocate upon the turret, dies mounted upon the turret, there being one of the dies for co-operation with each driver-assembly, means for pressing the work during the operation upon it against the turret-structure, and an abutment member secured to the frame and against which the turret may bear to resist this application of pressure.
26. In a fastening-inserting machine, a carrier-plate in which are openings arranged in accordance with an inserting design, and an inserting die secured to one side of the plate and provided with a depression and with a die-tube extending through each carrier-plate-opening, said die-tube having a head situated in the depression and a projection at the opposite side of the die from the depression.
27. In a fastening-inserting machine, a carrier-plate in which are openings arranged in accordance with an inserting design, an inserting die secured to one side of the plate and provided with a depression and with a die-tube extending through each carrier-plate-opening, said die-tube having a head situated in the depression and a projection at the opposite side of the die from the depression, and a holder for a work-piece attached to the turret-plate and extending about tube-projections.
28. In a heel-attaching machine, a rotatable carrier provided with vertical ways, a slide movable in the ways and having a projection in which are horizontal ways, a driver-holder separably mounted in the slide-ways and having vertical ways, a driver-plate with its drivers secured to the holder, a breast-slide movable in the holder-ways, and a breast-driver-plate and its drivers secured to the breast-slide.
29. In a fastening-inserting machine, reciprocatory fastening-drivers, a reciprocatory actuating member, and yieldable means transmitting

movement of the actuating member to the drivers and arranged to apply to the drivers a decreasing force as the resistance encountered by said drivers increases.

5 30. In a fastening-inserting machine, reciprocating fastening-drivers, a reciprocating actuating member, a compression-spring, and a member acting to compress the spring and connected to the drivers and their actuating member, such 10 connections being arranged to decrease the force exerted by the spring as the resistance encountered by the drivers increases.

15 31. In a fastening-inserting machine, reciprocating fastening-drivers, a reciprocating actuating member, a spring, and a toggle-lever connected to both the drivers and the actuating member and acting upon the spring.

20 32. In a fastening-inserting machine, reciprocating fastening-drivers, a reciprocating actuating member, a spring, and a toggle-lever the links of which are connected at their outer extremities to the drivers and actuating member respectively and at their inner connected ends acting to compress the spring.

25 33. In a fastening-inserting machine, reciprocating fastening-drivers, a reciprocating actuating member, a pivoted casing, a plunger movable in the casing, and a toggle-lever joined at its center to the plunger and at its outer extremities 30 to the drivers and actuating member respectively.

35 34. In a fastening-inserting machine, a frame, side-rods reciprocating therein, a top-girt secured to the side-rods, drivers mounted upon the top-girt, a cross-girt secured to the side-rods, a crosshead reciprocable in the frame, a toggle-lever connected at its opposite extremities to the cross-girt and crosshead respectively, and a spring upon which the toggle-lever acts at its center.

40 35. In a fastening-inserting machine, a frame, side-rods reciprocating therein, a top-girt secured to the side-rods, drivers mounted upon the top-girt, a cross-girt secured to the side-rods, a crosshead reciprocable in the frame, a casing pivoted upon the crosshead, a compression-spring within the casing, a plunger movable in the casing to compress the spring, and a toggle-lever connected to the crosshead, the cross-girt and the plunger.

45 36. In a fastening-inserting machine, reciprocating fastening-drivers a portion of which are yieldable independently of their companions, a reciprocating actuating member, and yieldable means transmitting movement of the actuating member to the drivers and arranged to apply to the drivers a decreasing force as the resistance encountered by said drivers increases.

50 37. In a fastening-inserting machine, reciprocating fastening-drivers a portion of which are yieldable independently of their companions, a reciprocating actuating member, and a plurality of yieldable means transmitting movement of the actuating member to the drivers and arranged to apply to the drivers a decreasing force as the resistance encountered by said drivers increases.

55 38. In a fastening-inserting machine, a frame, side-rods reciprocating therein, a top-girt secured to the side-rods, drivers movable upon the top-girt, a toggle-lever pivoted to the top-girt and acting upon the drivers, and a spring carried by the top-girt and resisting movement of the toggle-lever.

60 39. In a fastening-inserting machine, a frame, side-rods reciprocating therein, a top-girt se-

cured to the side-rods, drivers movable upon the top-girt, a toggle-lever pivoted at one extremity to the top-girt and acting at its opposite extremity upon the drivers, a rod joined to the center of the toggle-lever and guided in the top-girt, 5 and a spring surrounding the rod and compressed by movement of the toggle-lever.

40 30. In a fastening-inserting machine, a frame, a work-support carried thereby, a turret rotatable upon the frame, a plurality of inserting dies 10 and co-operating reciprocating driver-assemblies mounted upon the turret and movable thereby into operating position at the work-support, and a reciprocating actuating member into engagement with which any one of the driver-assemblies 15 may be brought and acting to lower and raise said assemblies.

41. In a fastening-inserting machine, a frame, a work-support carried thereby, a turret rotatable upon the frame, a plurality of inserting dies 20 and co-operating reciprocating driver-assemblies mounted upon the turret and movable thereby into operating position at the work-support, opposite side-rods arranged to reciprocate in the frame, and a top-girt fast upon the side-rods, 25 and by which the driver-assembly in operating position may be actuated.

42. In a fastening-inserting machine, a frame, a work-support carried thereby, a turret rotatable upon the frame, a plurality of inserting dies 30 and co-operating reciprocating driver-assemblies mounted upon the turret and movable thereby into operating position at the work-support, opposite side-rods arranged to reciprocate in the frame, a top-girt fast upon the side-rods and by 35 which the driver-assembly in operating position may be actuated, means for reciprocating the side-rods, and yieldable connections between said means and the side-rods.

43. In a fastening-inserting machine, a rotatable turret provided with a circular series of vertical ways, inserting dies mounted upon the turret, slides movable in said ways and having portions from which are arcuate projections, driver-assemblies carried by the slides and co-operating with the dies, and a reciprocating actuating member provided with arcuate ways to receive the arcuate projections of the slides.

44. In a fastening-inserting machine, a work-support, a rotatable turret, a plurality of fastening-inserting means movable upon the turret and movable thereby into operating position at the work-support, means for locking the fastening-inserting means against movement upon the turret, and means acting in the rotation of the turret for unlocking the fastening-inserting means.

45. In a fastening-inserting machine, a work-support, a rotatable turret, a plurality of fastening-inserting means movable upon the turret and movable thereby into operating position at the work-support, means for locking the fastening-inserting means against movement upon the turret, and means acting in the rotation of the turret for unlocking the fastening-inserting means 60 and for simultaneously positioning the turret 65 with a particular fastening-inserting means in operating position.

46. In a fastening-inserting machine, a work-support, a rotatable turret, a plurality of fastening-inserting means movable upon the turret and movable thereby into operating position at the work-support, means for locking the fastening-inserting means against movement upon the turret, means acting in the rotation of the turret 70 and for simultaneously positioning the turret 75 with a particular fastening-inserting means.

- for unlocking the fastening-inserting means, and means for locking the turret with the positioned fastening-inserting member in its operating position.
- 5 47. In a heel-attaching machine, a jack, a rotatable turret, a plurality of driver-slides reciprocable upon the turret and any one of which may co-operate with the jack, a locking member for each slide movable upon the turret, and means fixed relatively to the turret for operating the locking member.
- 10 48. In a heel-attaching machine, a frame provided with a cam-surface, a jack mounted upon the frame, a turret rotatable upon said frame, a plurality of driver-slides reciprocable in the turret and any one of which may co-operate with the jack, and a locking member for each slide movable upon the turret and controlled by the frame-cam.
- 15 49. In a heel-attaching machine, a frame provided with a cam-surface, a jack mounted upon the frame, a turret rotatable upon said frame, a plurality of driver-slides reciprocable in the turret and any one of which may co-operate with the jack, and a member for each slide movable by the frame-cam to lock its slide and releasing said slide only when it is in operating position at the jack.
- 20 50. In a heel-attaching machine, a jack, a rotatable turret, a plurality of driver-slides reciprocable upon the turret and any one of which may co-operate with the jack, a locking member for each slide movable upon the turret, and means fixed relatively to the turret for operating the locking member, said means being arranged to determine the position of the turret.
- 25 51. In a heel-attaching machine, a frame provided with a cam-surface in which is a depression, a jack mounted upon the frame, a turret rotatable upon said frame, a plurality of driver-slides reciprocable in the turret and any one of which may co-operate with the jack, and a locking member for each slide movable upon the turret and entering the cam-depression to determine the position of the turret.
- 30 52. In a heel-attaching machine, a jack, a rotatable turret, a plurality of driver-slides reciprocable upon the turret, a locking member for each slide movable upon the turret and arranged to unlock its slide when in operating position at the jack, automatic means for moving the locking member, and means movable by the operator for locking the turret with the unlocked slide in operating position.
- 35 53. In a heel-attaching machine, a jack, a rotatable turret, a plurality of driver-slides reciprocable upon the turret, a reciprocatory member arranged to actuate a driver-slide located in operating position at the jack, and a locking member for the turret movable upon the actuating member.
- 40 54. In a heel-attaching machine, a frame provided with a cam-surface, a jack mounted upon the frame, a turret rotatable upon said frame, a plurality of driver-slides reciprocable in the frame, a top-girt fixed to the side-rods and having means for actuating the driver-slide in operating position at the jack, and a locking member movable upon the top-girt into engagement with the slide.
- 45 55. In a fastening-inserting machine, a work-support, members reciprocable to successively prick the work and insert fastenings therein, and a cam rotatable through 360° to reciprocate the drivers through different distances for producing

the pricking and inserting strokes of the drivers.

56. In a heel-attaching machine, a frame, a jack mounted thereon, a die, side-rods reciprocable in the frame, a top-girt fixed to the side-rods, members mounted upon the top-girt and movable thereby to successively prick the work and insert fastenings therein, and a cam rotatable upon the frame through 360° to reciprocate the side-rods twice for producing the picking and inserting strokes of the drivers.

10 57. In a fastening-inserting machine, a casing provided with an opening, fastening-inserting mechanism carried by the casing, a removable closure for the casing-opening, and mechanism for feeding strings of fastening-material to the inserting mechanism, said feeding mechanism being mounted upon the closure and removable as a unit therewith.

15 58. In a fastening-inserting machine, a casing provided with an opening, fastening-inserting mechanism carried by the casing, a removable closure for the casing-opening, a feeder-frame fixed to the closure, a feeder-roll rotatable upon the frame, a swinging frame pivoted upon the fixed frame, and a feeder-roll rotatable upon the swinging frame and co-operating with the companion roll.

20 59. In a fastening-inserting machine, a work-support, a movable carrier, a plurality of fastening-inserting mechanisms mounted upon the carrier and movable thereby into operating position at the work-support, mechanism by which fastening-material may be fed into the path of the movable carrier, means for operating said mechanism under the power of the machine, and means arranged for manual actuation to disconnect the feeding mechanism from the power means and to operate said feeding mechanism.

25 60. In a fastening-inserting machine, a work-support, a movable carrier, a plurality of fastening-inserting mechanisms mounted upon the carrier and movable thereby into operating position at the work-support, rotatable rolls by which strings of the fastening-material may be fed to the inserting mechanism which is at the operating position, a shaft for rotating the rolls, ratchet mechanism by which the shaft is rotated, and a hand-wheel movable to connect the ratchet mechanism to and disconnect it from the shaft and for rotating said shaft.

30 61. In a fastening-inserting machine, a work-support, a movable carrier, a plurality of fastening-inserting mechanisms mounted upon the carrier and movable thereby into operating position at the work-support, rotatable rolls by which strings of the fastening-material may be fed to the inserting mechanism which is at the operating position, a shaft for rotating the rolls, ratchet mechanism by which the shaft is rotated, a sleeve splined for movement longitudinally of the shaft, means whereby the sleeve may separably engage the ratchet mechanism, and means arranged to move the sleeve longitudinally of the shaft and to rotate said sleeve.

35 62. In a fastening-inserting machine, a work-support, a rotatable turret provided with a plurality of inserting dies having fastening-receiving passages and companion driver-assemblies, feeding mechanism stationary with respect to the rotation of the turret and having rotatable rolls by which the strings of fastening-material may be fed into the die-passages, means for rotating the rolls under the power of the machine to feed the strings forward into the die-passages, and means arranged for actuation by the oper-

- ator for disconnecting the rolls from the power mechanism and for rotating said rolls in opposite directions.
63. In a fastening-inserting machine, inserting mechanism having a reciprocatory driver-assembly, actuating mechanism for the driver-assembly, mechanism for feeding string-material to the inserting mechanism, a member movable to actuate the feeding mechanism, a connecting member movable upon the actuating member into opposite extremes of engagement therewith, and connections to the actuating mechanism for the driver-assembly for thus moving the connecting member.
64. In a fastening-inserting machine, inserting mechanism having a reciprocatory driver-assembly, actuating mechanism for the driver-assembly, mechanism for feeding string-material to the inserting mechanism, a reciprocatory member by 20 which the feeding mechanism is actuated, and a link pivoted upon the reciprocatory member and connected to the actuating mechanism, said link being movable idly about its pivot into contact with the reciprocatory member and then actively 25 to move said member.
65. In a fastening-inserting machine, a frame, side-rods reciprocable therein, inserting mechanism actuated by the side-rods, rotatable rolls for feeding string fastening-material to the inserting mechanism, a reciprocatory rack by which the rolls are rotated, and connections to a side-rod for reciprocating the rack.
66. In a fastening-inserting machine, a frame, side-rods reciprocable therein, inserting mechanism actuated by the side-rods, rotatable rolls for feeding string fastening-material to the inserting mechanism, a reciprocatory rack by which the rolls are rotated, a link pivoted upon the rack and movable between opposite points into engagement therewith, and means joined to the side-rods for actuating the link.
67. In a fastening-inserting machine, a frame, a turret rotatable upon the frame and provided with a plurality of fastening-inserting mechanisms, any one of which may be brought into operating position, a tube-assembly mounted upon the turret in co-operation with each inserting mechanism, mechanism for feeding strings of fastening-material, tubes through which the strings are fed from such feeding mechanism, and a stationary terminal member for the tubes, the tube assemblies of the turret moving into registration with the tubes at the terminal in the rotation of the turret.
68. In a fastening-inserting machine, a frame, a turret rotatable upon the frame and provided with a plurality of fastening-inserting mechanisms, any one of which may be brought into operating position, a tube-assembly mounted upon the turret in co-operation with each inserting mechanism, a bar in which the tubes of the assembly terminate, mechanism for feeding strings of fastening-material, tubes through which the strings are fed from such mechanism, a bracket secured to the frame, and a bar attached to the bracket and in which the tubes from the feeding mechanism terminate and into co-operation with which each of the tube-bars of the turret may move.
69. In a fastening-inserting machine, fastening-inserting mechanism, means for supplying string fastening-material, and means having a compound movement of rotation and translation for cutting fastenings from the string-material and transferring them to the inserting mechanism.
70. In a fastening-inserting machine, fastening-inserting mechanism, means for supplying string fastening-material, a fastening-loading member movable between the supplying means and the inserting mechanism, and means for rotating the loading member at the supplying means to sever fastenings from the string and for moving said member bodily to transfer the severed fastenings to the inserting mechanism.
71. In a fastening-inserting machine, inserting mechanism having fastening-receiving passages, mechanism provided with fastening-supplying passages, a cutting and transferring member movable between the two mechanisms, and means for imparting to the member a compound movement to carry its passages from alinement with those of the supplying mechanism into alinement with those of the inserting mechanism.
72. In a fastening-inserting machine, inserting mechanism having fastening-receiving passages, 20 mechanism provided with fastening-supplying passages, a cutting and transferring member movable bodily from one extreme of travel with its passages alined with the fastening-supplying passages to the opposite extreme at which its 25 passages register with those of the inserting mechanism, and a revolute actuating member for the cutting and transferring member effective to impart thereto its cutting movement as said revolute member passes the center farthest 30 removed from the inserting mechanism.
73. In a fastening-inserting machine, fastening-inserting mechanism, means for supplying string fastening-material, a rotatable loader-block provided with passages and being movable 35 between the supplying means and the inserting mechanism, and a crank-pin for actuating the loader-block, said crank-pin as it passes the center removed from the inserting mechanism being arranged to rotate the block at the supplying 40 means.
74. In a fastening-inserting machine, inserting mechanism, supplying mechanism for strings of fastening-material, a reciprocatory slide, a loader-block movable upon the slide and by said slide between the supplying and inserting mechanisms, and a revolute actuating member connected to the loader-block.
75. In a fastening-inserting machine, inserting mechanism, supplying mechanism for strings of fastening-material, a reciprocatory slide, a loader-block movable upon the slide and by said slide between the supplying and inserting mechanisms and having an arm extending from it, and a revolute actuating member connected to the 55 arm.
76. In a fastening-inserting machine, inserting mechanism, supplying mechanism for strings of fastening-material, a reciprocatory slide, a loader-block rotatable upon the slide and movable by 60 said slide between the supplying and inserting mechanisms, and a revolute pin connected to the loader-block.
77. In a fastening-inserting machine, inserting mechanism having fastening-receiving passages, 65 mechanism provided with fastening-supplying passages, a reciprocatory slide, a loader-block rotatable upon the slide and having passages which may register with those of the supplying and inserting mechanisms, and means for rotating the loader-block upon the slide to sever the fastenings and for reciprocating the slide to present the severed fastenings to the inserting mechanism.
78. In a fastening-inserting machine, inserting 75

mechanism having fastening-receiving passages, mechanism provided with fastening-supplying passages, a reciprocating slide, a loader-block rotatable upon the slide and having passages which may register with those of the supplying and inserting mechanisms, and a revolute crank-pin connected to the block and movable across the path of the slide to sever the fastenings.

79. In a fastening-inserting machine, a work-support, a movable carrier, a plurality of fastening-inserting mechanisms mounted upon the carrier and each having a die and co-operating drivers, each mechanism being movable selectively as a unit by the carrier into operating position at the work-support, and means arranged to supply liquid to the inserting mechanisms.

80. In a fastening-inserting machine, a work-support, a movable carrier, a plurality of fastening-inserting mechanisms mounted upon the carrier and each having a die and co-operating drivers, each mechanism being movable selectively as a unit by the carrier into operating position at the work-support, and means arranged to supply liquid only to the inserting mechanism which is in operating position.

81. In a fastening-inserting machine, a work-support, a rotatable turret, a plurality of fastening-inserting mechanisms mounted upon the turret, each mechanism having a die provided with passages and being movable by the turret into operating position at the work-support, and means arranged to deliver liquid to the passages in the die which is in operating position.

82. In a fastening-inserting machine, a work-support, a rotatable turret, a plurality of fastening-inserting mechanisms mounted upon the turret, each mechanism having a die provided with passages and being movable by the turret into operating position at the work-support, and means arranged to deliver liquid to the passages in the die which is in operating position and to draw the liquid from said die.

83. In a fastening-inserting machine, a work-support, a rotatable turret, a plurality of fastening-inserting mechanisms mounted upon the turret, each mechanism having a die provided with passages and being movable by the turret into operating position at the work-support, there being passages in the turret leading to the die-passages, a member fixed relatively to the rotatable turret and provided with a passage delivering to the turret-passages, a pump, and a pipe connecting the pump to the passage in the member and through which liquid is supplied and withdrawn from the die-passages.

84. In a fastening-inserting machine, a work-support, a rotatable turret, a plurality of fastening-inserting mechanisms mounted upon the turret, each mechanism having a die provided with passages and being movable by the turret into operating position at the work-support, there being a passage in the turret individual to each of the dies, a member fixed relatively to the rotatable turret and provided with a passage registering only with the turret-passage of the die which is in operating position, and means arranged to deliver liquid to the passage in the fixed member.

85. In a fastening-inserting machine, a work-support, a rotatable turret, a plurality of fastening-inserting mechanisms mounted upon the turret, each mechanism having a die provided with passages and being movable by the turret

into operating position at the work-support, there being a passage in the turret individual to each of the dies, a member fixed relatively to the rotatable turret and provided with a passage registering only with the turret-passage of the die which is in operating position and with a passage registering with the passages of the other dies, and means arranged to deliver liquid to the passage in the fixed member which is joined to the die in operating position and to withdraw liquid from the other passage in the fixed member.

86. In a heel-attaching machine, a casing, a turret rotatable upon the casing and having a head provided with liquid-distributing passages, inserting dies mounted upon the turret and provided with passages to which the distributing passages are connected, and a bracket secured to the casing and having a surface in close contact with which is movable a surface of the head, there being a passage in the bracket delivering liquid to the turret-passages.

87. In a heel-attaching machine, a casing, a turret rotatable upon the casing and having a head provided with liquid-distributing passages, inserting dies mounted upon the turret and provided with passages to which the distributing passages are connected, and a bracket secured to the casing and having a surface in close contact with which is movable a surface of the head, there being a passage in the bracket which may register with any one of the head-passages and a passage registering with the other head-passages.

88. In a fastening-inserting machine, inserting mechanism having a die in which are fastening-receiving passages, absorbent material carried by the die at the entrances to the passages and means for delivering liquid to the absorbent material.

89. In a heel-attaching machine, a carrier-plate provided with openings, a die secured to the under side of the plate and having a groove opposite the openings and openings through the die into the groove, tubes extending through the plate-openings and having heads in the groove of the die and heel-engaging projections below the die, and drivers movable in the tubes.

90. In a heel-attaching machine, a carrier-plate provided with openings, a die secured to the under side of the plate and having a groove opposite the openings and openings through the die into the groove, tubes extending through the plate-openings and having heads in the groove of the die and heel-engaging projections below the die, there being slots opening through the tube-heads from the groove, means for delivering liquid to the groove, and drivers movable in the tubes.

91. In a heel-attaching machine, a carrier-plate provided with openings, a die secured to the under side of the plate and having a groove opposite the openings and openings through the die into the groove, tubes extending through the plate-openings and having heads in the groove of the die and heel-engaging projections below the die, there being slots opening through the heads from the groove, means for delivering liquid to the groove, absorbent material surrounding the heads in the tubes, and drivers movable in the tubes.

FRED N. LA CHAPELLE.
